P. THIBODEAU

CURTAIN FIXTURE

Filed April 28, 1923

UNITED STATES PATENT OFFICE.

PETER THIBODEAU, OF HOLYOKE, MASSACHUSETTS, ASSIGNOR OF ONE-HALF TO
DAVID H. YOUNG, OF HOLYOKE, MASSACHUSETTS.

CURTAIN FIXTURE.

Application filed April 28, 1923. Serial No. 635,211.

To all whom it may concern:

Be it known that I, PETER THIBODEAU, a citizen of the United States of America, residing at Holyoke, county of Hampden, 5 Commonwealth of Massachusetts, have invented certain new and useful Improvements in Curtain Fixtures, of which the following is a specification.

This invention relates to improvements in 10 curtain fixtures for supporting a plurality of curtains or draperies.

An object of the invention is to provide a plurality of hinged supporting rods that may be swung from a common center or 15 support so that when one rod is pulled out the other will be moved with it for permitting easy access to the window for washing or cleaning purposes.

A further object is to provide a third 20 rod which may be attached to and removed from the common supporting bracket of the hinged rods.

A further object is to provide means for 25 removing one set of the plurality of rods and simply using the remaining set when lace or other curtains alone are to be used, the drapery rods being detached.

A further object is to form the ends of 30 the rods with curves so that the curtains may be moved on the rods around the curved portion and close to the window casing or framework.

These and other objects of the invention 35 will appear in the body of the specification and will be pointed out in the claims.

Referring to the drawings:

Fig. 1 is a plain view showing the plurality of rods that are connected to the common support or center and a third rod attached outside of the other rods and below the same.

Fig. 2 is a side elevational view partly in section substantially on the line 2—2 of Fig. 1 showing the relation of the two 45 connecting rods and the detachable one below the same.

Fig. 3 is an enlarged detail plan view of the manner of connecting the two rods together so that when one is moved the other will be moved with it.

Fig. 4 is a detail side elevational view on an enlarged scale showing the manner of connecting the two rods or a pair of them

together and supporting them about a common pivotal center. 55

Fig. 5 is a plan view of one end of the inner and lower rod.

Fig. 6 is a bottom plan view of the rod which is located outside of the inner rod and showing the recess therein for receiving a lug or projection of the inner or lower rod, and 60

Fig. 7 is a detail perspective view of one of the brackets for attaching a pair of rods to the window frame or casing. 65

Referring to the drawings in detail:

1 designates the upper casing or framework of the window, 2 brackets which are attached thereto at the opposite ends by any suitable means as the screws 3. 4 is 70 an opening which extends vertically through each of the brackets. 5 designates a curtain rod which is formed with a head portion 6 having an opening 7 which extend through the cylindrical shaped bearing part 8. The part 8 enters the opening 4 of the bracket, as shown in Fig. 4. The head portion 6 is formed with two shoulders 9 and 10 to serve as stops which engage the lug 11 on the bracket 2 (see 80 Fig. 7), when the rod 5 is swung in opposite directions as indicated by the two arrows 12 and 13 in Fig. 3. 14 is a lug on the head portion 6. This lug enters the recessed part 15 of a second curtain 85 rod 16 which is located in front of and parallel with the rod 5 as shown in Fig. 1. A bottom plan view of the head end of this second rod is shown in Fig. 6. 17 designates a cylindrical shaped bearing part 90 on the rod 16 which enters the opening 7 of the rod 5 when the two rods are assembled on the bracket 2, as shown in Fig. 3; the lug 14 then enters the recess 15 as shown.

18 designates the head part of the rod 95 16. As shown in Fig. 1 the rods 5 and 16 are arranged or located one in front of the other in spaced parallel relation and in the same horizontal plane. The lug 14 on the rod 5 which enters the recess on the rod 100 16 causes the two rods to turn together when either one is moved toward or away from the window as shown in dotted lines in Fig. 1. The shoulder 9 on the rod 5 striking the lug 11 on the bracket 2 limits 105 their inward movement and the shoulder

10 of the rod 5 striking the other side of the lug 11 limits their outward movement. In other words when one rod is moved or turned in the bracket 2 the other will move or turn in unison therewith.

19 designates a tubular member which is slipped or slid over the outer end of each of the rods 5 and 16 in order to close or span the window space or width. 20 are 10 plugs which enter the ends of the tubular members 19, which are provided with the heads 20' for retaining the curtains in place on the rods. It is obvious that only one pair of rods, as 5 may be used, the other 15 pair 6 being removed from the support by withdrawing the cylindrical member 17 from the opening 7 indicated in dotted lines in Fig. 4. If desired the plugs 20 may be removed and one of the tubular members 20 19 slipped or moved along one of the rods 5 on the end of the other rod 5.

21 designates a third or other rods which are located below and parallel with the rods 5 and 16. Each of these rods are formed 25 with projections 22 which enter openings in the brackets 23 located below the brackets 2. If desired the rods 21 may be removed from the brackets 23 and their projections 22 placed in the recesses 24 indicated in dotted lines in Fig. 2. 25 designates a tubular or sleeve member which is slipped over the adjacent inner ends of the two members 21.

An important feature of my improvement 35 is in the curving of the inner ends of all of the rods so that the curtains may be moved on the rods and close to the window casings thus obviating an opening between the edges of the curtains and the window casings.

The rods 5 may be employed for receiving 40 lace curtains, the rods 16 may be employed for receiving the heavier hangings or curtains, and the rods 21 may be employed for receiving any ornamental or finishing hangings.

45 For this description it will be seen that I have provided two pairs of curtain rods that may be swung as a unit, and a construction which will permit one pair to be removed, and a further construction which 50 will permit a third rod to be used separately or with the other rods.

What I claim is:

1. In a curtain construction for windows, 55 the combination, of a pair of rods in the same horizontal plane for supporting separate curtains, means for pivotally supporting the same on a common support, means for moving one rod from the other comprising a lug on one and a recess on the other to freely receive the lug, said construction permitting one rod to be freely lifted or detached from the other.

2. In a curtain rod construction for windows, the combination, of a pair of rods in

the same plane for supporting separate curtains, means for pivotally supporting the same on a common support, means for moving one rod from the other comprising a lug on one and a recess on the other to freely receive the lug, stop shoulders on one of the rods, said construction permitting one rod to be freely lifted or detached from the other, and cooperating means between the shoulders on one of the rods and the common support to limit the outward and inward movements of the pair of rods when moved as a unit.

3. In a curtain construction for windows, the combination, of a pair of rods for supporting separate curtains, means for pivotally supporting the same on a common support, a stop lug on the support, means for moving one rod from the other comprising a lug on one and a recess on the other to freely receive the lug, said construction permitting one rod to be freely lifted or detached from the other and cooperating means between shoulders on one of the rods to limit the outward and inward movements of the pair of rods when moved as a unit, 90 said means including a lug or stop on the common support and shoulders on one of the pairs of rods for engaging the shoulders.

4. A curtain rod construction, comprising 95 in combination, of a pair of rods located in the same plane and in spaced parallel relation, a common supporting bracket, the inner ends of the rods being placed one over the other, the lower rod having a part which enters the bracket and formed with a lug 100 and two shoulders, the upper rod having a recess on its lower side to receive the lug of the lower rod to cause the two rods to move together, the bracket having a lug with which the two shoulders of the lower rod 105 engages to limit the outward and inward movements of the two rods.

5. A curtain rod construction, comprising 110 in combination, of a pair of rods located in the same plane and in spaced parallel relation, a common supporting bracket, the inner ends of the rods being placed one over the other, the lower rod having a part which enters the bracket and formed with a lug 115 and two shoulders, the upper rod having a recess on its lower side to receive the lug of the lower rod to cause the two rods to move together, the bracket having a lug with which the two shoulders of the lower rod 120 engages to limit the outward and inward movements of the two rods each of the upper rods having a recess to receive a projection of a third rod, whereby three distinct curtain rods are provided, said rods being each provided with slidable tubular or sleeve members to vary the length of the rods.

PETER THIBODEAU.
